REFILL FUSE PLUG

John Cree and David Anthony Worme, Hamilton,
Ontario, Canada

Application August 10, 1939, Serial No. 289,442

7 Claims. (Cl. 200—125)

Our invention relates to improvements in refill fuse plugs and an object of the invention is to devise a plug adapted to contain a plurality of separate fuse elements wherein any selected 5 fuse element of the plurality may be thrown into circuit without removing the plug from the socket or holder when one of the fuse elements which has previously been in circuit is fused by an overload.

10 A further object is to devise a refill fuse plug in which the plurality of fuse elements may be inserted and removed from the plug as a unit instead of separately.

15 A still further object is to provide an improved fuse element of bi-metallic construction particularly adapted for use with our plug wherein the ends are constructed of a metal insusceptible to fusing under ordinary overloads, whereas the body is composed of the orthodox 20 fuse metal capable of fusing upon being subjected to current greater than for which it is designed.

25 With the above and other objects in view which will hereinafter appear as our specification proceeds, our invention consists, in its preferred construction, of the construction and arrangement all as hereinafter more particularly described and illustrated in the accompanying drawing in which:

30 Fig. 1 represents a vertical section through a fuse holder or socket of the screw shell type showing our refill fuse plug (in elevation) screwed thereto.

35 Fig. 2 is a vertical section of our plug taken on the line 2—2 (Fig. 4).

Fig. 3 is a vertical section thereof taken on the line 3—3 (Fig. 4), the capsule being shown in elevation.

40 Fig. 4 is a top plan view of our plug.

Fig. 5 is a side view of the insulating body of 45 our plug.

Fig. 6 is an inverted plan view thereof.

Fig. 7 is a top plan view of the capsule showing the plurality of fuse elements mounted thereon.

Fig. 8 is an inverted plan view thereof partly in section.

Fig. 9 is an elevational detail of a manually 50 operable rotatable contact for throwing any selected fuse element into circuit.

Fig. 10 is a detail in plan showing the means for mounting the fuse elements whereby they may be inserted into and removed from the capsule as a unit, and

Figs. 11 and 12 are respectively plan and edge views of one of our bi-metallic fuse elements.

Like characters of reference indicate corresponding parts in the different views of the drawing.

5 Our refill fuse plug comprises an exteriorly threaded cylindrical insulating body 1 preferably composed of heat resisting glass with a peripheral flange 2 (by means of which the plug is screwed into and unscrewed from the screw shell 10 10 3 of the holder 4) in the vicinity of its closed end 5. The other end of the body 1 is open and provided with a plurality of spaced apart notches 6.

15 The capsule 7 of insulating material such as porcelain is generally cylindrical in shape and hollow and has a circumferential flange 8 there-around intermediately of its length with a plurality of spaced apart lugs 9 on the upper face of such flange adapted to be inserted into the 20 notches 6 when the capsule 7 is inserted into the body 1 with its flange 8 resting on the lip of the open end of the body. The interior of the capsule has a central contact receiving bore 10 of reduced diameter at its lower end and the 25 upper lip of the capsule is provided with diametrical extending grooves 11. The wall of the upper part 12 of the capsule is provided with a plurality of vertical spaced apart fuse element 30 receiving grooves 13 with their inner surfaces concave in longitudinal section, said grooves being located on the capsule between the lugs 9 on its flange 8.

35 The plurality of fuse elements each comprises a strip of fuse metal 14 forming the body of the fuse element and end strips 15 of normally non-fusible metal such as copper, sweated or otherwise secured to the strip 14. The upper end strips 15 are hooked around the periphery 40 of an insulating disc 16 and through spaced apart slots 17 in the vicinity of its periphery located in radial grooves 18 in the top of the disc, the lower end strips 15 being hooked about the flange 8 of the capsule 7 also in spaced relation 45 so that the fuse element portions 14 lie in the vertical grooves 13 in the capsule wall leaving air spaces between the portions 14 and the inner surfaces of such grooves.

The insulating disc 16 having a central orifice 50 19 therethrough is detachably mounted on the upper end of the capsule 7 with pimples 20 inserted into the diametrical grooves 11 for preventing it rotating relatively to the capsule, and is held on such capsule by the lower ends 15 of 55

fuse elements being hooked over the flange 8 as above referred to.

A metallic screw shell 21 having an inturned flange 22 at its outer end defining a central circular opening to receive the lower part 23 of the capsule is threaded onto the body 1 until its flange 22 abuts the flange 8 of the capsule and makes electrical contact with the lower ends 15 of the fuse elements. An upwardly extending resilient lug 24 formed on the upper end of the screw shell 21 is adapted to be inserted into an indentation 25 in the body 1 for positively locking the screw shell 21 to the body against relative rotation when the plug is screwed into the holder 4.

When the plug is disconnected from the holder the lug 24 does not lock the screw shell 21 to the body as the lug is not then located in the indentation 25 having, due to its resiliency, disengaged itself therefrom.

Prior to the application of the screw shell 21 to the body 1 a spindle 26 carrying the central contact 27 at its lower end is inserted into the capsule with the contact 27 extending through the bore 10 and protruding therefrom. The contact 27 is provided with an air vent 27a in the form of a vertical slit in its periphery. The upper end of the spindle extends freely through an orifice 28 in the upper end 5 of the body 1 and has a squared extremity 29 protruding exteriorly thereof to which is cemented or otherwise secured the actuating knob 30.

A boss 31 is provided on the spindle 26 intermediately of its length from which extends a radial finger contact 32 adapted to make contact with the respective upper ends 15 of the fuse elements. A leaf spring 33 having a central orifice 34 is provided on the spindle 26 between the boss 31 and the upper end 5 of the body 1.

Radial fuse indicating notches 35 are located on the flange 2 of the body 1 in register with the grooves 13 in the capsule and therefore with the fuse elements therein, and similar notches or serrations 36 may be provided on the knob 30.

When the plug is once screwed into the holder it is unnecessary to remove it until all the fuses are burnt out. The finger contact 32 is initially set by rotating the spindle by means of the knob 30 so that such finger contacts with the upper end 15 of any one fuse element. When such fuse element due to overload is burnt out, it is only necessary to pull out the knob a limited extent against the action of the spring 33 and rotate the spindle until the finger contact enters the next radial slot 18 wherein the finger makes contact with the upper end 15 of the next fuse element.

The provision of the vent 27a and the radial grooves 11 as well as the concave surfaces in the grooves 13 enables the gases resulting from the fusing of the fuse elements to be adequately vented.

When all the fuse elements attached to the disc have been burnt out the plug may be removed and the screw shell 21 unscrewed from the body. The capsule may then be removed, leaving the spindle 26 in position, and the unfused portions of the fuse elements may then be detached from the capsule flange and disc and replaced by a fresh supply of fuse elements when the plug may be then reassembled. Alternatively, if desired, the refill instead of consisting of new fuse elements alone may consist of a new disc as well with the new fuse elements already assembled thereon.

What I claim as my invention is:

1. A fuse plug comprising an externally thread-

ed hollow body of insulating material open at one end, a hollow fuse element carrying capsule of insulating material having a peripheral outwardly directed flange extending therearound intermediately of its length, said flange adapted to seat on the lip of the open end of the body, a plurality of independent fuse elements entirely mounted on the side and one end of the exterior of the capsule, a metallic screw shell adapted to be screwed on the threaded body and make electrical contact with the corresponding end of each fuse element located on the side of the exterior of the capsule, and means in the body including operable means disposed exteriorly thereof for selectively making electrical contact with the other ends of the fuse elements on the end of the capsule.

2. The invention claimed in claim 1 wherein a member of insulating material is superimposed on the inner end of the capsule and the ends of the fuse elements adapted to make contact with the contact means in the body are attached to such member, and such contact means in the body is rotatable axially therein and includes an outwardly extending contact adapted to make electrical contact selectively with the respective ends of the fuse elements attached to the member of insulating material.

3. The invention claimed in claim 1 wherein a disc of insulating material having a plurality of radial grooves in a face thereof with slots in such grooves in the vicinity of its periphery is mounted on the capsule, and the ends of the fuse elements adapted to make contact with the contact means in the body are hooked through the slots and extend into the grooves, said contact means in the body being axially rotatable, and an outwardly extending contact on the contact means in the body adapted to make electrical contact selectively with the respective ends of the fuse elements extending into the grooves in the disc.

4. The invention claimed in claim 1 wherein a disc of insulating material having a plurality of radial grooves in a face thereof with slots in such grooves in the vicinity of its periphery is mounted on the capsule, and the ends of the fuse elements adapted to make contact with the contact means in the body are hooked through the slots and extend into the grooves, said contact means comprising a longitudinally movable and rotatable metallic spindle extending axially and freely through the body, disc and capsule and including a contact protruding from the outer end of the capsule and an outwardly extending contact located intermediately of the length of the spindle for selectively making electrical contact with the respective ends of the fuse elements extending into the grooves in the disc.

5. The invention claimed in claim 1 wherein a disc of insulating material having a plurality of radial grooves in a face thereof with slots in such grooves in the vicinity of its periphery is mounted on the capsule, and the ends of the fuse elements adapted to make contact with the contact means in the body are hooked through the slots and extend into the grooves, said contact means comprising a longitudinally movable and rotatable metallic spindle extending axially and freely through the body, disc and capsule and including a contact protruding from the outer end of the capsule and an outwardly extending contact located intermediately of the length of the spindle for selectively making electrical contact with the respective ends of the fuse elements extending

into the grooves in the disc, said spindle protruding exteriorly of the body, and a knob of insulating material on such protruding end.

6. The invention claimed in claim 1 wherein a plurality of spaced apart longitudinal grooves are provided on the exterior of the capsule and the fuse elements are receivable thereinto, the inner surfaces of such grooves being concave in longitudinal section to space the fuse elements dis-

posed therein from such inner surfaces.

7. In a fuse plug, a removable capsule of in-

sulating material having a peripheral flange extending therearound intermediately of its height, a member of insulating material superimposed on the capsule, and a plurality of independent fuse elements attached in spaced relation at their upper ends to the member and extending down the exterior of the capsule, and hook-shaped lower ends on the fuse elements adapted to be hooked over the peripheral edge of the flange.

JOHN CREE.
DAVID ANTHONY WORME.
